MOVABLE RACK FOR ROLL PAPER PRODUCTS

John J. M. Larson, Des Peres, Mo., assignor to Graham Paper Company, St. Louis, Mo., a corporation of Missouri

Filed May 3, 1968, Ser. No. 11,782

Term of patent 14 years

Int. Cl. D19—99

U.S. Cl. D52—2

The single figure is a perspective view of a movable rack for roll paper products embodying my new design. I claim:

The ornamental design for a movable rack for roll paper products, substantially as shown.
